UNITED STATES PATENT OFFICE.

PERCY MORRIS AND JOHN OLIVER BRYANT, OF LONDON, ENGLAND, ASSIGNORS TO
WHITEHEAD, MORRIS & COMPANY, LIMITED, OF LONDON, ENGLAND.

COMMERCIAL PAPER.

1,269,487.

Specification of Letters Patent. Patented June 11, 1918.

No Drawing.

Application filed July 30, 1914. Serial No. 854,179.

To all whom it may concern:

Be it known that we, PERCY MORRIS and JOHN OLIVER BRYANT, both subjects of the King of Great Britain, and both residing 5 at 9 and 10 Fenchurch street, London, England, have invented new and useful Improvements in Commercial Paper; and we do hereby declare that the following is a full, clear, and exact description of the invention, which will enable others skilled in the art to which it appertains to make and use the same.

This invention relates to the printing and producing of checks, drafts, letters of credit, 15 promissory notes and the like, hereinafter referred to as drafts, in which an amount, and (or) other matter, is written, generally by one of the parties thereto.

The practice of fraudulently altering the 20 amount or the written matter on drafts is very common and the present invention has for its object to render the alteration more difficult to accomplish than heretofore without showing on the face of the document 25 that the alteration has been made.

It is usual in a draft to have some safety ground which will not interfere with the distinctness of the matter written thereon, and this safety ground most frequently consists of the name of the bank or other information in very small words. Various methods and processes have been used for printing this safety ground work, and the principal method hitherto in vogue, has been 35 to use fugitive inks, and inks made with anilin dyes.

These inks have, however, always been in the nature of "printing" inks, that is to say, inks which have had the necessary consistency or oiliness which has made them adaptable for the ordinary processes of printing. The use of ordinary writing ink, in the same chemical condition as that in which it is used for writing, has not been 45 contemplated, and the very fact of using a "printing" ink as heretofore, in itself provides the possibility of altering the check or note, on which the amount of other matter is written in ordinary writing ink.

50 A common method of altering a draft involves a differential treatment of the safety ground and of the written matter thereon, and consists in first treating the safety ground with a mordant that will not affect the written matter, and in then dis-

solving, bleaching or washing off the written matter with a suitable chemical, thereby leaving a more or less clean safety ground to be again written on.

Now, according to the present invention 60 the ink in which the safety ground is produced is of a nature substantially similar to that used for writing thereon, and in substantially the same chemical condition in which it is used for writing, and without 65 any thickening or other doctoring, so that if an attempt is made to alter the draft, then whatever change is produced in the safety ground will also be produced in the matter written thereon, whereby a differential treatment, as described above, is not possible. 70

The simplest and most practical method of carrying out the present invention is to produce or print the safety ground with an 75 ink in aqueous solution such, for example, as any ordinary fluid ink that is used for writing, say one of the well known proprietary inks, and preferably one of the blue or blue-black inks. Ordinarily writing inks, 80 i. e. inks in aqueous solution have not hitherto been used for printing purposes without being doctored or modified to make them suitable for this purpose, such as by thickening with oil, glycerin, or other vehicle. If, however, any doctoring or modification of any kind whatsoever of the ink takes place to enable it to be used for printing, and it is to be used for the purpose of printing the groundwork, the very fact of 85 the doctoring offers an opportunity for a differential treatment of the groundwork and of the written matter thereover. If, however, the ink used for the groundwork is identical with the ink used for writing, 90 this draw back is avoided and the possibility of such differential treatment is removed. 95

Another possible and prior method for defeating alteration is to modify the printing 100 ink used for the groundwork to render it suitable for writing purposes, but this as a general proposition would involve introducing and marketing a special writing ink, and is not a practical proposition. 105

Any difficulty in producing a good impression, with an aqueous or writing ink, of a safety ground such as ordinarily adopted, i. e. one composed of a fine linework design or informative matter in very small 110

type can be overcome and a good impression produced by using on the printing machine between the distributing drum and the inking bed or table, a distributer or distributers 5 (or vibrator or vibrators) having a plush or like soft absorbent carrying surface. Any difficulty in producing a good impression, with untreated aqueous or writing ink, of a safety ground work such as ordinarily used 10 on checks, *i. e.* fine line work or informative matter in small type, may be overcome by the following means. In the printing machine, a vibrator, oscillating between the distributing drum and the inking bed, has 15 a plush or other absorbent surface; the distributers for distributing the ink, on the surface of the inking bed may have a plush, rubber or like surface. To prevent any chemical modification of the ink, the use of 20 any metal surfaces, with which the ink would react, is avoided. Thus, if a trough feed is used, the trough may be made of glass, also a glass inking slab may be employed and if a metal printing surface is 25 used, it may be coated with platinum.

A further modification of the present invention comprises the production and use 30 of a groundwork in a plurality of colors, one or more of the printings of such groundwork being printed in an aqueous ink such as writing ink, which has not been doctored or otherwise modified to change it into a printing ink. The purpose and utility of such multicolor groundwork will be appar-

ent by the following example. If a groundwork is produced in, say, two or three colors, so chosen and printed as to present the appearance of a neutral tint, and if one of these colors is in ordinary writing ink, and the other colors are in printing ink, or colored writing inks, then if the writing on the draft is altered the consequent alteration of the portion of the groundwork in writing ink will visibly alter the color and appearance of the groundwork on the draft. 35 40 45

Claims:

1. Sheet material, provided with a printed ground of ordinary fluid writing ink and adapted to receive characters, applied in ordinary fluid writing ink, of substantially the same chemical composition. 50

2. Paper, provided with a printed ground of ordinary fluid writing ink and adapted to receive characters applied in the same identical ink. 55

3. Commercial paper, provided with a safety ground applied to its surface with ordinary fluid writing ink, substantially the same in chemical composition and condition as that in which it is used for writing, 60 whereby alteration, without detection, of matter subsequently written thereon, is prevented.

PERCY MORRIS.

JOHN OLIVER BRYANT.
